Primary Examiner — Clare E Heflin(74) *Attorney, Agent, or Firm* — East West Law Group; Heedong Chae(57) **CLAIM**

The ornamental design for an LED lighting fixture, as shown and described.

DESCRIPTION

FIG. 1 is a top perspective view of the LED lighting fixture showing my new design;

FIG. 2 is a top view thereof;

FIG. 3 is a bottom view thereof;

FIG. 4 is a another perspective view thereof;

FIG. 5 is a rear perspective view thereof;

FIG. 6 is an enlarged cross-sectional view thereof taken along the line 6-6 in FIG. 3; and,

FIG. 7 is an enlarged fragmentary perspective view thereof, taken within the circle 7 in FIG. 5.

The broken line showing of environment is for illustrative purposes only and forms no part of the claimed design.
